ALPHONSE LECOMTE, OF SWANSEA, MASSACHUSETTS, ASSIGNOR TO DRAPER CORPORATION, OF HOPEDALE, MASSACHUSETTS, A CORPORATION OF MAINE.

TAKE-UP MECHANISM FOR LOOMS.

Application filed November 19, 1923. Serial No. 675,584.

To all whom it may concern:

Be it known that I, ALPHONSE LECOMTE, a citizen of the United States, and resident of Swansea, in the county of Bristol and 5 State of Massachusetts, have invented an Improvement in Take-Up Mechanisms for Looms, of which the following description, in connection with the accompanying drawings, is a specification, like characters on 10 the drawings representing like parts.

This invention relates to take-up mechanisms for looms by which the cloth is taken up and wound upon a warp beam or roll as it is woven. The warp threads extend 15 from the let-off mechanism to the take-up roll and the threads are let off by the let-off mechanism as the cloth is woven. It is now the general practice to lead the woven cloth over a take-up roll and to operate this 20 roll at such a rate that as the cloth is woven the "fell" of the cloth will be presented to the reed to cause the filling or weft thread to be properly beaten up. The take-up roll is given its rotative movement from a train 25 of mechanism driven from an actuator connected with a rotating part of the loom.

It sometimes happens that the take-up action or pull of the take-up roll on the cloth becomes excessive due to various causes, such 30 as the cloth becoming wrapped around the take-up roll, or tucked under the part of the cloth leading over the roll.

When this happens, regardless of the primary cause of the excessive or abnormal opposition to the rotation of the take-up roll, undue strain is developed in the take-up mechanism, and if the take-up roll continues to operate, injury either to the cloth, 35 the warp threads or the take-up mechanism 40 may result.

In accordance with the present invention, when the take-up roll or transmission mechanism is subjected to an excessive strain that would be likely to injure either the cloth, the warp threads, or the transmission 45 mechanism, the take-up action of the take-up roll is suspended while the loom continues in operation.

In the drawings:

50 Fig. 1 is a perspective view showing one form of take-up mechanism employing the present invention;

Fig. 2 is an enlarged side view with parts in section of gears having cooperating projections in gripping engagement;

Fig. 3 is a side view of parts shown in Fig. 1;

Fig. 4 is a view similar to that of Fig. 2, but showing the cooperating projections out of gripping engagement; 60

Fig. 5 is a perspective view of one of the cooperating gears; and

Fig. 6 is a perspective view of the other 65 cooperating gear.

The loom frame comprises the usual side frames 1 connected by cross-pieces 2 for supporting the working parts of the loom. The take-up roll 3 is shown as a rough surface 4 and this roll is supported upon a shaft 5, the ends of which are journaled 70 in bearings supported at the sides of the loom frame. The cloth *a* passes over the take-up roll 3 and is wound upon the take-up beam or cloth roll beneath. In the loom construction shown, the cloth roll 6 75 is mounted upon a shaft 7, the ends of which are journaled in slots formed in the upper portion of the slides 8, one at each side of the loom. The slides 8 are yieldingly forced upwardly to press the upper face of 80 the cloth roll 6 against the take-up roll 3, and this is accomplished by providing a gear 9 to engage the rack portion 10 of each slide, and the gear 9 is normally urged in a direction to force the slide 8 upwardly 85 by a coiled spring 11 which is coiled about and serves to rotate a shaft upon which the gear 9 is mounted. In this manner the cloth roll 6 is yieldingly held against the take-up roll 3 and yields downwardly to 90 accommodate the increase in the size of this roll. This construction, however, is well known, and forms no part of the present invention.

In accordance with the present invention, the take-up mechanism for rotating the take-up roll 3 is operated by an actuator, and between the actuator and the take-up roll is provided a train of mechanism including a give-way device 100 which operates automatically to interrupt the transmission of power to the take-up roll when the latter encounters dangerous opposition to its rotation.

The actuator in the construction shown 105 comprises a gear 12 on a shaft 13 journaled in suitable bearings, and the shaft 13 is driven from a shaft 14 by a worm 15 and gear 16. The shaft 14 in turn is driven by bevelled gears from a shaft 17. 110

In the construction shown the actuator 12 meshes with a gear 18 which is rotatably supported upon a side of the loom frame by the shaft 19, and the gear 18 is provided with a long pinion 20 rigidly secured thereto. Above the shaft 19 is provided a gear 21 rotatably mounted upon a shaft 22 and the gear 21 meshes with and drives the gear 23 secured to the take-up roll shaft 5. Referring to Fig. 3 it will be noted that the gear 21 does not mesh with the pinion 20 but movement is imparted from the gear 20 to a driven gear 24 rotatably mounted upon a shaft 25, and upon the shaft is also mounted the driving gear 26 which meshes with and drives the gear 21.

In order that the take-up roll 3 may stop rotating when too great a tension is placed upon the cloth *a*, a give-way device is provided, and in the embodiment of the invention illustrated this is accomplished by providing interengaging projections upon the gears 24 and 26, as best shown in Figs. 5 and 6. These projections, designated by 27 and 28, have inclined edges, as best shown in Figs. 2 and 4, which tend to force the gears apart as the power imparted from one gear to the other increases, and the gear 24 is normally urged towards the gear 26 by a coiled spring 29. One end of this spring is seated within an annular groove formed in a face of the gear 24, while the opposite end of this spring abuts against a washer 30 mounted upon the shaft 25 and secured thereupon by a cotter pin 31. The tension of the spring 29 is such that it will normally hold the gear 24 in driving engagement with the gear 26, as shown in Fig. 2, and the parts will remain in this relation throughout the normal operation of the loom, but if, for any reason, the rotation of the take-up roll is abnormally obstructed, the cooperating projections 27 and 28 will move out of driving engagement with each other, as shown in Fig. 4. Since the pinion 20 is made relatively long, the gear 24 may be slid lengthwise of the shaft 25 without becoming disengaged from the pinion 20.

The shaft 25 preferably is supported by the change gear support 32 whereby the shaft 25 may be moved angularly relative to the shaft 19 by swinging the support 32 to the desired position of adjustment and then tightening up the clamp nut 33, and the shaft 25 may be moved towards and from the gear 21 by moving the same to different positions of adjustment within the slot 34 formed in a downwardly extending arm 35 of the support 32.

From the foregoing description when read in connection with the drawings it will be seen that the give-way device of the present invention may be readily applied to looms now in use, as the shaft 25 provided with the gears 24 and 26 and means for

imparting movement from one to the other may be easily secured to the change gear support 32 in place of the ordinary change gears heretofore used in the chain of gears employed to impart rotary movement to the take-up roll from an actuator 12. It will be understood that the actuator may be of any usual type, and that the actuator continues in operation during the continued weaving operation of the loom, even though the take-up roll is permitted to stop by the give-way device.

What is claimed is:

1. In a take-up mechanism for looms, the combination of a driven cloth take-up roll over which the cloth passes and by which the cloth is taken up as woven, a cloth winding roll to which the cloth is delivered as it is drawn frontward by the take-up roll, an actuator, a train of mechanism between the actuator and take-up roll for causing the take-up roll to take up the cloth as it is woven and including an elongated transmission gear which is constantly driven, a driven gear constantly engaging therewith; a shaft on which it is mounted for movement longitudinally thereof, a driving gear also on said shaft, interlocking projections between the driven and driving gears having inclined cooperating walls, and a spring acting on one of said gears to hold the projections normally interlocked and yieldable to automatically release the projections when rotation of the take-up roll is abnormally obstructed.

2. In a take-up mechanism for looms, the combination of a cloth take-up roll over which the cloth passes and by which the cloth is taken up as woven, an actuator, a train of mechanism mounted at one side of the loom between the take-up roll and actuator, including a shaft; a transmitting gear and a give-way gear mounted on the shaft, interengaging projections on the gears having inclined portions, yielding means normally acting to hold the projections in operative engagement and yieldable to permit automatic disengagement of the projections by an abnormal increased strain exerted by the cloth, and a constantly driven elongated gear the teeth of which are engaged by the give-way gear in its different positions along the shaft on which it is mounted.

3. In a take-up mechanism for looms, the combination of a cloth take-up roll over which the cloth passes and by which the cloth is taken up as woven, a train of mechanism between the take-up roll and an operating shaft of the loom for rotating the take-up roll to take up the cloth as it is woven and including a constantly actuated elongated gear, a driven gear in constant engagement with the elongated gear, a driving gear, a shaft upon which both of the gears are mounted, interlocking means be-

- between said gears, a spring acting on one of said gears to hold the gears normally interlocked and yieldable to permit relative rotation between the gears when rotation of the take-up roll is abnormally obstructed, and means for supporting said shaft in different positions of angular adjustment to permit the introduction of different sized gears thereupon.
4. In a take-up mechanism for looms, the combination of a take-up roll over which the cloth passes as it is woven, a cloth winding roll to which the cloth is delivered by the take-up roll, an actuator, a train of mechanism mounted at the side of the loom and between the take-up roll and actuator, including a transmitting gear and a concentrically mounted give-way gear, a constantly driven elongated gear meshing with the give-way gear, interengaging projections on the transmission and give-way gears, a spring normally acting to hold the projections in operative engagement and yieldable to permit automatic disengagement of the projections between the two gears by an

abnormally increased strain exerted by the cloth on the take-up roll.

5. In a take-up mechanism for looms, the combination of a driven take-up roll, a cloth beam to which the cloth is delivered by the driven take-up roll, an actuator for the take-up roll, an elongated gear which is constantly driven from the actuator, a shaft parallel to the axis of the elongated gear, a driving gear mounted on the shaft and connected to the take-up roll, a driven gear also mounted on said shaft for movement longitudinally thereof, projections on the two last named gears, a spring normally acting on the driven gear to maintain the projections in driving engagement, said projections having inclined portions for automatically causing movement of the driven gear along the shaft against the spring pressure by the opposition to rotation exerted on the driving gear through undue strain upon the cloth.

In testimony whereof, I have signed my name to this specification.

ALPHONSE LECOMTE.
